CHARLES LYNE, OF PADSTOW, ENGLAND.

Letters Patent No. 89,058, dated April 20, 1869; antedated April 6, 1869.

IMPROVEMENT IN FOLDING PERAMBULATOR.

The Schedule referred to in these Letters Patent and making part of the same

To all whom it may concern:

Be it known that I, CHARLES LYNE, of Padstow, county of Cornwall, England, have invented a new and improved "Folding Perambulator;" and I do hereby declare that the following is a full, clear, and exact description of the construction and operation of the same, reference being had to the accompanying drawings, making a part of this specification, in which—

Figure 1 is a side view of my improved perambulator extended and ready for use.

Figure 2 is a front view of same.

Figure 3 is a side view, folded.

The nature of my invention consists in constructing a folding perambulator, as herein set forth, so as to be readily transported, or carried with the parties having it in use, and is especially adapted for invalids, on account of its ease and comfort.

To enable others skilled in the art to make and use my invention, I will now proceed to describe its construction and operation.

The body, or framing of the perambulator, consists of four wooden or metallic uprights, A and A', and B and B', stiffened by braces, e and e', and d and d', connecting A and A' with B and B', and secured to and working on bolts, rods, or screws, are cross-pieces, e and e', f and f', and g and g'.

The braces e and e' form the back, on which is placed suitable material, stuffed, and provided with springs, to give it elasticity.

Stretched over and secured to braces e and e', is a webbing, or any suitable material to form a seat, and on which is placed a spring-cushion.

Cross-pieces e and e' form the arms, or rest, and are made in two pieces, and secured together on the under part, by hinges, as shown in figs. 1 and 2.

Cross-pieces g and g' extend out in front, and are stiffened by means of brace d. The parts of g and g' which extend out are boarded over, and form the foot-board, or rest for the feet.

Extending out in the rear of the body, and running under and secured to cross-pieces f and f', are steel springs, s and s', fig. 2, to which are secured an iron or wooden axle, A, and wheels W and W', of ordinary construction.

Secured to braces d and d', and the lower part curved, so as to come immediately under the foot-board, are steel springs, s² and s'.

The ends of said springs are formed with an eye, in which is inserted an axle, having on it a hub, provided with wheels, W² and W'.

Secured to the back of the body, on braces e and e', are round, oval, or flat irons, stiffened at the top by a brace, and the whole formed to serve as a handle, H, for operating and guiding the perambulator.

Secured to the top of brace d', and passing down and over the top of the foot-board, is a canvas covering, or carpet.

When it is desired to protect those using the perambulator from rain or sun, I secure an apron, or cover, as shown in red lines, fig. 1.

Having thus described my invention, its construction and operation,

What I claim, and desire to secure by Letters Patent of the United States, is—

The within-described folding perambulator, arranged, constructed, and operating substantially as specified.

CHARLES LYNE.
